(57) **CLAIM**

The ornamental design for a helmet shroud, as shown and described.

DESCRIPTION

FIG. 1 is a front, top, left-side, perspective view of a helmet shroud showing my new design;

FIG. 2 is a rear, bottom, right-side, perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines immediately adjacent the shaded areas represent the bounds of the claimed design while all other broken lines are directed to environment and are for illustrative purposes only; the broken lines form no part of the claimed design.

1 Claim, 5 Drawing Sheets
